US00D801296S

(12) **United States Design Patent** (10) **Patent No.:** **US D801,296 S**
(45) **Date of Patent:** **** Oct. 31, 2017**

(54) **PORTABLE ELECTRONIC DEVICE**

- (71) Applicant: **HTC Corporation**, Taoyuan (TW)
- (72) Inventors: **Catherine Sayim Kim**, San Francisco, CA (US); **Hannes Jens Dieter Harms**, San Francisco, CA (US); **Benjamin Scott Avery**, San Francisco, CA (US); **Benjamin Kai Norman Robertson**, San Francisco, CA (US); **Kristina Nicole Marrero**, San Francisco, CA (US)
- (73) Assignee: **HTC Corporation**, Taoyuan (TW)
- (**) Term: **15 Years**
- (21) Appl. No.: **29/551,426**
- (22) Filed: **Jan. 13, 2016**
- (51) LOC (10) Cl. **14-03**
- (52) U.S. Cl. **D14/138 G**

CLAIM

The ornamental design for portable electronic device, as shown and described.

DESCRIPTION

FIG. 1 is a front perspective view of a first embodiment of a portable electronic device in accordance with our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front perspective view of a second embodiment of a portable electronic device in accordance with our new design;

FIG. 10 is a rear perspective view thereof;

FIG. 11 is a front view thereof;

FIG. 12 is a rear view thereof;

FIG. 13 is a left side view thereof;

FIG. 14 is a right side view thereof;

FIG. 15 is a top plan view thereof; and,

FIG. 16 is a bottom plan view thereof.

The broken lines, which show portions of the portable electronic device, form no part of the second embodiment.

1 Claim, 14 Drawing Sheets
